UNITED STATES PATENT OFFICE.

THOMAS VILLAGE, OF SOUTH NORWALK, ASSIGNOR TO THE BRANFORD LOCK WORKS, OF BRANFORD, CONNECTICUT.

DESIGN FOR THE ORNAMENTATION OF BUILDERS' HARDWARE.

SPECIFICATION forming part of Design No. 18,357, dated May 29, 1888.

Application filed April 23, 1888. Serial No. 271,641. Term of patent 7 years.

To all whom it may concern:

Be it known that I, THOMAS VILLAGE, of South Norwalk, in the county of Fairfield and State of Connecticut, have invented a new Design for the Ornamentation of Builders' Hardware; and I do hereby declare the following, when taken in connection with accompanying drawing and the letters of reference marked thereon, to be a full, clear, and exact description of the same, and which said drawing constitutes part of this specification, and represents a face view of an escutcheon-plate embodying the design.

This invention relates to a design for the ornamentation of articles commonly called "builders' hardware," and such as are used for window, door, and house trimmings generally; and the invention consists of an ornamentation for the surface of such articles, representing a tracery of sea-weed interspersed with shells.

In representing the design I show an escutcheon-plate for door-trimmings, this being sufficient to illustrate the design in its application to builders' hardware generally. Around the outer edge is a representation of a series of shells forming a border. On the surface

within said border is the representation of a tracery of sea-weed interspersed with representation of shells as lying upon the surface, 3c and as shown in the accompanying illustration.

It will be understood that the shape of the article will to some extent change the general arrangement of the representation of sea-weed and shells; but the illustration which I have made will be sufficient to enable others skilled in the art to which this design relates to apply the design to the surface of various articles which go to make up the class to which 40 this design particularly relates.

I claim—

The herein-described design for the ornamentation of articles of builders' hardware, consisting in a border representing a series 45 of shells, the surface within said border ornamented with a representation of a tracery of a sea-weed interspersed with shells as lying upon the surface, substantially as shown in the accompanying illustration.

THOMAS VILLAGE.
